TO JAMES K. LANNING, OF BOSTON, MASSACHUSETTS.

KNOT-TYING IMPLEMENT.

1,094,915.

Specification of Letters Patent. Patented Apr. 28, 1914.

Application filed March 22, 1909, Serial No. 484,948. Renewed June 1, 1912. Serial No. 701,049.

To all whom it may concern:

Be it known that I, JAMES F. MATTHEWS, a citizen of the United States, residing at Pottersville, in the county of Bristol and State of Massachusetts, have invented an Improvement in Knot-Tying Implements, of which the following description, in connection with the accompanying drawings, is a specification, like letters on the drawings representing like parts.

This invention relates to knot tying implements particularly intended for use in piecing up the broken ends of spooling machines. It, however, is capable of use in other relations and for other purposes.

In order that the principles of the invention may readily be understood, I have disclosed a single embodiment thereof in the accompanying drawing, wherein—

Figure 1 is a side elevation of a knot tying implement embodying my invention; Fig. 2 is a front end elevation thereof; Fig. 3 is a plan view of the implement and showing the first position of the threads thereon; and Figs. 4, 5, 6 and 7 are enlarged views of a portion of the implement illustrating the several steps of the knot forming operation.

While the knot tying implement of my invention may be of general application, it is particularly intended for use in piecing up broken ends in a spooler. When an end is broken, the operative usually places the left hand upon the spool to stop its rotation upon its spindle and with the other hand grasps the broken ends extending from the spool and the bobbin in its holder, both hands being used to tie the knot.

While the implement herein disclosed may be supported upon the hand of the operative in any suitable manner, it is preferably supported upon the left hand; that is to say, upon the hand used to stop the rotation of the spool whose end is broken. Preferably also the implement is supported upon the forefinger of the left hand and in such manner that the knot tying operation can be performed wholly by the right hand of the user, as will be more fully described. The knot tied is what is known as the spooler's knot.

Referring more particularly to the drawing, the knot tying implement comprises a preferably metallic piece or strip 1, herein

termed a base or thread receiver. Attached thereto in any suitable manner is a ring 2, 55 within which a digit of the user and preferably the forefinger of the left hand may be inserted. I contemplate adapting the ring 2 to fingers of different size. To that end I may either attach the ring to the 60 base, but in such manner as to permit it to be readily disconnected and a different sized ring substituted, or as shown in Fig. 2 I may form the ring as an open one and of material which may be readily bent so that the 65 ring may be expanded or contracted to the proper size. If the ring be detachable, it may be secured in any suitable manner, as by means of a screw. If permanently attached it may be connected to the base in any suit- 70 able manner or formed therewith.

The base or thread receiver 1 is provided with an extension 3 constituting a bight former, herein shown as reversely bent and having side guiding edges 3^a, 3^b, and hav- 75 ing at its end a knot former 4 shown as an eye or looper and positioned preferably at a slight distance from and substantially parallel with the base 1 and also preferably transversely thereof, the bight former 3 be- 80 ing shown as twisted as at 5 to bring the knot former 4 into the transverse position described. In this embodiment of the invention, the bight former is shown as formed with and overhanging the base or 85 receiver 1.

I preferably provide a thread introducing guide and a thread exit guide. The thread introducing guide is here represented as a preferably metallic piece 6 secured to 90 the under face of the base 1 and extending upwardly adjacent the inner edge of such base. The thread exit guide is represented as a notch or slot 7 formed in the base pref- 95 erably immediately beneath the knot former 4. If desired, the edge leading to the exit guide may be inclined thereto as represented at 8.

I provide any suitable means to sever the threads after the formation of the knot, 100 and to that end may provide any suitable construction of movable blade or may pro- 105 vide the base 1 with a sharpened edge or attach thereto a stationary blade in proper relation to the knot former 4. In the present embodiment of the invention, I have,

however, illustrated a blade 9 adapted to be operated by the user and preferably by the thumb of the hand whereon the implement is carried. Herein the blade 9 is represented as pivoted at 10 upon the rear end of the base 1 and as having a downwardly bent thumb piece 11 which may receive the pressure of the thumb to force it against the threads. The base is provided with a spring 12 to return the blade to non-severing position.

If in use the implement is mounted upon the left hand of the operative, the broken ends may be grasped in the right hand and introduced through the guide 6 and led across the base 1 in the manner indicated at 13 in Fig. 3. The threads then lie back of and below the knot former 4. The threads are then by the right hand slid along the remote or outer edge of the base 1, this edge serving to guide the threads in their movement. In this manner the threads are brought above the eye or looper 4, the threads extending from above the eye to the outer guiding edge 3^a of the bight former 3, as illustrated in Fig. 4. The movement of the right hand carrying the threads is continued, the hand being moved in a curve from a position back of the implement and from substantially the plane of the base 1 to a point in front thereof. This wraps the threads in parallelism in a common bight about the bight former 3, bringing the free ends of the threads guided by the edges 3^a, 3^b, down into the knot former 4 in the manner illustrated in Fig. 5. Further pull upon the threads draws them off the tongue 14, so that the threads are held by the hook 15 of the knot former 4, as illustrated in Fig. 6, 40 the knot lying between the thread introducing guide 6 and the knot former 4. When the threads are in this position the ends are severed by movement of the blade 9. The blade does not in this embodiment of the invention make a shear cut, but the threads are, in the described operation, drawn sufficiently taut for severance by the blade. After the thread ends have been severed, the severed ends cling slightly to the hook 15, 50 as represented in Fig. 7, so that in practice the operative may take hold of one of the thread ends now joined and remove her left hand from the spool. By taking hold of one of the thread ends at this point in the operation a kink is prevented. That is to say, the threads are prevented from twisting together above the knot as is now done in certain types of knot tying devices. Moreover the operative can at a glance inspect 55 the knot while the thread end is held by the hand. This can be done without appreciable loss of time. By drawing upon the joined threads the knot falls off the hook 15 and the operation is completed.

From the foregoing description, it will be apparent that the knot tying implement of my invention is one which permits the very rapid tying of the knot and also permits inspection of the knot before it is released and avoids all kinking or twisting together of the threads. As the implement can be carried upon a finger of that hand which is usually placed upon the spool to stop its rotation when an end breaks down, the operative has one hand wholly free for manipulating the thread and can if desired readily sever the thread by the thumb or another finger of the hand whereon the implement is mounted. Furthermore the implement is exceedingly simple and inexpensive and does not have parts liable to get out of order or to become broken.

Having thus described one illustrative embodiment of my invention, I desire it to be understood that although specific terms are employed, they are used in a generic and descriptive sense and not for purposes of limitation, the scope of the invention being set forth in the following claims.

Claims:

1. A knot tying implement comprising a thread receiver having a reversely extending portion constituting a bight former about which both threads are to be wrapped in parallelism to form a bight therein, said bight former having as a unitary member thereof a terminal knot former to which said threads may be drawn along the former while so wrapped.

2. A knot tying implement comprising a thread receiver having a bight former about which both threads are to be wrapped in parallelism to form a bight therein, said bight former having an end directed toward and adjacent said receiver and having a knot former to receive said threads.

3. A knot tying implement comprising a thread receiver having a bight former about which both threads are to be wrapped in parallelism to form a bight therein, said bight former having a terminal knot former and a side guiding edge along which said threads may be guided to the knot former.

4. A knot tying implement comprising a thread receiver having a reversely bent portion overhanging the base of the receiver and provided with a knot former.

5. A knot tying implement comprising a thread receiver or base having a return portion extending along said base and having a bight former about which the threads are to be wrapped to form a bight, said bight former having opposed guiding edges and the end portion of said bight former having a knot former unitary therewith.

6. A knot tying implement comprising a thread receiver having a bight former about which the threads are to be wrapped to

form a bight, said bight former having a knot former, and thread severing means, said knot former being positioned between said thread severing means and the body 5 of the bight former.

7. A knot tying implement comprising a thread receiver having a unitary bight former about which a pair of threads are to be wrapped to form a common bight, said 10 bight former having a knot former provided with integral knot supporting means having a blunt, non-cutting contour and upon which means the knot may be drawn tight while so supported.

15. 8. A knot tying implement comprising a thread receiver or base having a return portion extending along said base, and provided with a knot former, said implement having thread severing means.

20. 9. A knot tying implement comprising a thread receiver having a bight former about which a pair of threads are to be wrapped to form a common bight, said bight former being bent and extending at an angle to the 25 receiver and having an open eye extending transversely to the receiver, into which the free ends of said pair of threads may be conducted after the formation of the bight.

10. A knot tying implement comprising a 30 thread receiver having a bight former about which a pair of threads are to be wrapped to form a common bight, said bight former having an open eye extending transversely to the receiver, into which the free ends of 35 said pair of threads may be conducted after the formation of the bight, means to sever said free ends and means to support the knotted threads after severing.

11. A knot tying implement comprising a 40 thread receiver having a bight former about which a pair of threads are to be wrapped to form a common bight, said bight former having an open eye extending transversely to the receiver, into which the free ends of 45 said pair of threads may be conducted after the formation of the bight, said bight former having a bight supporting hook adjacent said eye to support the knot after thread severance, and means to sever the free ends 50 of the threads.

12. A knot tying implement comprising a thread receiver having integral therewith a bight former about which a pair of threads are to be wrapped to form a common bight, 55 said bight former having an eye provided with a thread supporting projection and means to sever the free ends of the threads while still leaving the knotted portion supported upon said projection.

60. 13. A knot tying implement comprising a thread receiver having a portion bent to extend at an angle to said receiver and having a bight former about which a pair of threads are to be wrapped to form a com-

mon bight, said bight former having as a 65 unitary member thereof a terminal knot former for both said threads, and means to support the implement upon the hand of the operator.

14. A knot tying implement comprising a 70 base adapted to be supported upon the hand of the operator, said base having a bight former about which a pair of threads are to be wrapped to form a common bight, said bight former having as a unitary member 75 thereof a terminal knot former and severing means movable with respect to said bight former.

15. A knot tying implement comprising a 80 base adapted to be supported on a digit of the operator, and having a bight former about which a pair of threads are to be wrapped to form a common bight, said bight former having a knot forming eye, and means beyond said eye to sever the free ends 85 of said threads.

16. A knot tying implement comprising a base adapted to be supported on a digit of the operator, and having a bight former about which a pair of threads are to be 90 wrapped to form a common bight, said bight former having a terminal eye, and a digitally operated blade between the eye and base.

17. A knot tying implement comprising a 95 base having a thread introducing guide and a bight former having a terminating knot former, said base, at a point spaced and distinct from said knot former, having an exit guide to receive the free ends of the threads 100 extending from said knot former.

18. A knot tying implement comprising a base having a thread introducing guide and a bight former having a terminating knot former, said base having an exit guide 105 to receive the free ends of the threads extending from said knot former and a blade between said base and said knot former.

19. A knot tying implement comprising a thread receiving base adapted to be supported upon a digit of the operator, and having a thread guiding overhang terminating in an open eye transverse to and spaced from said base, the latter having a thread introducing and a thread exit guide and 115 thread severing means between the eye and exit guide.

20. A knot tying implement comprising a thread receiver or base having a return portion extending along said base and provided with a bight former about which both threads are to be wrapped in parallelism to form a bight therein, said bight former having integral therewith a knot former, to which said threads may be drawn along the 120 former while so wrapped, said implement having a digit receiving expandible member for supporting the implement in use. 125

21. A knot tying implement having a base, a unitary bight former extending therefrom having a knotting eye, a digit receiving member attached to said base, and a 5 digitally operated, spring retracted severing blade mounted upon said base.
22. A knot tying implement having a thread receiving base adapted to be supported on the hand of the operator and provided with a thread guiding overhang terminating in an open eye adjacent said base, said base and overhang being shaped to direct the body of the thread from below and behind said eye to a position thereover and 10 the free end of the thread into said eye.
23. A knot tying implement having a thread receiving base provided with a thread guiding overhang terminating in an open eye adjacent said base, said base and overhang being shaped to direct the body of the 15 thread from a position between the base and eye and behind the latter to a position across the eye and the free end of the thread into said eye.
24. A knot tying implement comprising a thread receiver having a return portion extending along said receiver and constituting a bight former about which a pair of threads are to be wrapped to form a common 20 bight, and having as a unitary member thereof a knot former, said implement having means to support it in use upon the forefinger of the user in fixed position for the application of said pair of threads thereto by the 25 other hand of the operator.
25. A knot tying implement to be carried by one hand of the user and comprising a base having a bight former about which a pair of threads are to be wrapped by the 30 other hand of the user to form a common bight, said bight former having as a unitary member thereof a knot former for both threads and to which both of said threads are to be manually drawn after the formation 35 of the bight, and severing means beyond said knot former.
26. A knot tying implement comprising a thread receiver having a bight former about which both threads are to be wrapped in 40 parallelism to form a bight therein, said bight former having a forked knot former unitary with said bight former and to which said threads may be drawn along the former while so wrapped, and severing means dis- 45 tinct from and beyond said knot former.
27. A knot tying implement comprising a thread receiver having a one-piece bight former about which a pair of threads are to 50
- be wrapped to form a common bight, said bight former having a knot former provided 60 with a knot supporting protruding hook having a blunt non-cutting contour and upon which hook the knot may be drawn tight while so supported.
28. A knot tying implement comprising a 65 thread receiver or base having a return portion extending along said base and provided with a knot former, and severing means between said base and knot former.
29. A knot tying implement having a 70 thread receiving base provided with a thread guiding return portion terminating in an open eye adjacent said base, said base and return portion being shaped to direct the body of the thread from a position 75 between the base and eye and at one side of the latter to a position across the eye and the free end of the thread into said eye.
30. A knot tying implement having a 80 thread receiving base adapted to be supported upon the hand of the operator and provided with a thread guiding portion having an eye adjacent said base, the latter being shaped to direct the body of the thread from below and behind said eye to a position 85 thereover and the free end of the thread into said eye.
31. A knot tying implement having a 90 thread receiving base provided with a portion having an eye adjacent said base, the latter being shaped to direct the body of the thread from a position between the base and eye, and behind the latter to a position 95 across the eye and the free end of the thread into said eye.
32. A knot tying implement comprising a thread receiver having a unitary bight former about which the threads are to be wrapped to form a bight, said bight former having a knot former and thread severing 100 means.
33. A knot tying implement comprising a thread receiver having a bight former about which the threads are adapted to be wrapped to form a bight, said bight former 105 having an eye and being shaped to direct the body of the thread to a position over the eye and the free end of the thread into the eye.
- In testimony whereof, I have signed my 110 name to this specification, in the presence of two subscribing witnesses.
